UNITED SHOE MACHINERY CORPORATION, OF PATERSON, NEW JERSEY, A CORPO-
RATION OF NEW JERSEY.

HEEL-PRESS.

1,281,360.

Specification of Letters Patent. Patented Oct. 15, 1918.

Application filed March 13, 1916. Serial No. 83,837.

To all whom it may concern:

Be it known that I, FRED V. HART, a citizen of the United States, residing at Lynn, in the county of Essex and State of Massachusetts, have invented certain new and useful Improvements in Heel-Presses; and I do hereby declare the following to be a full, clear, and exact description of the invention, such as will enable others skilled in the art 10 to which it appertains to make and use the same.

This invention relates to heel building machines and more particularly to heel block presses in which the pasted, built-up heel 15 piles are placed to prepare them for the compressing operation.

It has long been the practice to utilize a jack press in connection with the production of heels built from pasted lifts. The 20 type of press in general use for a long period of years was large enough to receive between the press plate or clamps a considerable number of heels laid out in rows on superposed boards. Before the quick setting paste now 25 used considerably was discovered, which has been termed a vulcanizing heel paste, it was necessary to leave the heels in the press at least 24 hours and sometimes several days before they dried out sufficiently to be fit to 30 be compressed. With the new type of press, hereinafter referred to, using a pressure of approximately 110 pounds, a period as short as five minutes has been found to be sufficient to produce a permanently cohering heel 35 pile. Increase of pressure shortens the period of time named. There has somewhat recently come into use a new type of heel press comprising a number of individual presses mounted on an endless carrier, the 40 freshly pasted heel piles being inserted individually between the open clamps of each press which, after the clamps are closed, pass through the orbit of the carrier and the heel is then ejected. The carrier is of such 45 size, compared to the pressure exerted on the heel, as to compel the heel pile to remain under pressure until the lifts firmly adhere. Such a machine, which may be used with either the new or the old paste, is illustrated 50 and described in my assignee's application for Letters Patent of the United States Serial No. 67,814, filed December 20, 1915.

The present invention is particularly adapted to a heel press of the general type 55 described in said application but those

skilled in the art will recognize that its utility is not limited to the presses of such a machine.

Before explaining the novel features of the present invention it is particularly 60 pointed out that in this specification the term "heel lift" is used inclusively to designate the pieces of material, of whatever nature they may be, that are utilized as the components of the heel being built, and the 65 term "heel block" is used to designate the product obtained by piling the pasted lifts prior to the compressing operation, that is, either the freshly pasted heel pile, which is a "wet" or "green" heel block, or the dry 70 pressed heel pile ready for the heel compressing operation, in order to distinguish this article from the commercial "heel blank" which is the product of the heel compressor.

Because of the extremely tenacious quality 75 of the vulcanizing heel paste and the thin film into which it is pressed by the clamps of the heel press it is extremely difficult to tear the lifts apart. This is of course true to a lesser 80 extent with the older paste. Consequently, it becomes very difficult to remove the heel block from the smooth faced clamps now in use on heel presses, if some of the paste being used has found its way between the 85 contacting surfaces of the block and clamping members. Unfortunately, due to the manner in which the heel piles are built, this latter condition is one which is the rule rather than the exception, that is, when the 90 heel blocks are ready for the pressing operation paste has been slopped upon and is adhering to their heel seats and tread faces with which the clamp members contact when the blocks are under pressure. As a result 95 it is only by means of a heavy blow that the heel blocks can be dislodged after the clamps are opened. The whole block is generally found to be stuck to one of the clamp plates as firmly as the individual lifts are stuck to 100 each other. It will be obvious that this is an extremely undesirable condition.

The object of the present invention is to overcome the sticking of the heel blocks to the clamp plates while still utilizing the 105 usual method of building heels which permits paste to adhere to the outer sides of the heel pile as well as to the inner faces of the lifts.

In accordance with this object it is pro- 110

posed to provide means for preventing an adherence of the block to the clamping plates. This is preferably accomplished by forming the block engaging faces of the 5 clamps in such a way as to prevent the paste from spreading, while under pressure, into a thin film between the heel block and the clamping members. Success in this respect has been secured by a reduction of the 10 surface of the clamping plates which contacts with the heel block, and to this end preferably the plates are formed with a broken or interrupted block engaging face, that is, with alternate raised and depressed portions. The plates thus offer too small a 15 contacting surface to permit a film of paste to form of sufficient area to cause an adherence. A further advantage is secured from such a formation of the clamps. The depressed portions of the plates provide paste 20 receiving containers whereby whatever paste may be on the outside of the heel block is kept in a thick enough layer to overcome its tendency to set during the time that the 25 heel block remains under pressure.

In the best form of the invention at present known each member of the clamp is provided in its heel block engaging surface with a series of channels spaced so close together 30 that the heel contacting portions of the clamping members are merely a series of long, narrow edges. The channels are made deep enough to contain such an amount of paste that it is still wet or fluid when the 35 heel block is ready to be ejected from the clamp. Under these conditions the heel block may readily be removed by the relatively light pressure exerted by a hand operated pusher or similar ejecting device.

40 To the accomplishment of the above object the invention comprises the novel features hereinafter explained in detail and then particularly pointed out in the appended claims.

45 In the accompanying drawings illustrating a preferred embodiment of the invention,

Figure 1 is a side elevation of a heel press clamp detached from the endless carrier 50 which sustains it and others like it.

Fig. 2 is a front elevation of the clamp shown in Fig. 1, the stippling indicating paste.

Fig. 3 is a perspective showing the under 55 heel block engaging face of the upper press plate or clamping member, detached, and

Fig. 4 is a perspective of the upper heel block engaging face of the lower press plate or clamping member, detached.

60 In the embodiment of the invention illustrated in the drawings the endless, flexible conveyer of the heel press which sustains the individual clamps is shown as a pair of parallel chains 5, each having a link 6 secured 65 by a rivet 7 to the under side of the clamp

frame plate 8. The frame plate surrounds the top of a tubular depending member 9, within which is a coiled spring 10 resting on a shelf at its bottom. A rod 11 extends through the spring 10 having a head 12 bearing on the spring and adjustable lock nuts 13 on its lower end, outside the member 9, which limit the upward movement of the rod. On the head 12 is supported the lower clamping member 14.

75 Rising from one side of the frame plate 8 is a rigid standard 15. Opposite the standard 15 is a second yieldingly held standard 16. The standard 16 is pivoted by its lower end to a lug 17 extending laterally from the member 9 and is held pressed inward, toward the frame plate 8, by a coiled spring 18 suitably connected by its ends to a lug on the standard and to the member 9. Each of the standards is provided with a series of bores 19 within which may rest the trunnions 20 of the pivotally mounted, adjustable upper clamping member 21.

80 It will be understood that the heel block 22 is clamped between the plates 14 and 21 of the clamp by the pressure exerted on the lower clamp plate by the spring 10 and that the clamp is opened and the heel block is released by compressing the spring in any suitable manner, as by downward pressure 85 on the arm 23 attached to the lower plate.

85 The novel feature of the clamp which forms the subject matter of the present application resides in the formation or configuration of its heel block engaging faces, that is, the provision of the paste receiving channels 24 and 25 in the upper and lower clamping members respectively. These are preferably in the form of semi-circular depressions extending in a parallel series across 105 the heel block contacting face of each plate. The two plates might be said to have corrugated pressing surfaces thus reducing the area of the plates which contacts with the heel block, it being obvious that only the 110 upper edges of the ridges press against the heel block. It should be understood, however, that the area of the portion of each plate which contacts with the heel block is maintained sufficiently great to permit a substantial pressure to be applied without disfigurement of the surface of the heel block.

115 The channels are deep enough, in practice about $\frac{1}{8}$ ", to receive and hold a layer of paste from the outside of the heel block sufficiently thick to prevent its drying while the heel block is in the press. Thus as the paste on the heel block, which contacts with the block contacting portions of the clamping members, is prevented from spreading into a thin film of sufficient area to cause adherence, the block is easily ejected. Furthermore, if the channels 24 become filled with paste such paste, because of its depth, will not dry and set. Thus the difficulty 120 125 130

of having the heel blocks adhere to the clamping members, with its attendant disadvantages hereinbefore pointed out, is overcome.

5 The preferred form of the clamping plates, that is, the provision of the channels 24 for reducing their block contacting surfaces, offers another advantage. By cutting the channels transversely of the conveyer 10 chains 5 (see Fig. 2) the ridges formed between them provide, substantially, tracks which assist the ejector, engaging the heel breast, in easily dislodging the heel block from the clamp at the completion of the 15 pressing operation. Because the usual form of ejector operates in a plane near the surface of the lower clamp plate 14, out of an abundance of caution, the edges of the ridges between the channels on the upper plate 21 20 are preferably rounded (see Fig. 3) so as to offer no flat surface whatever to retain a film of paste between the clamp and block, and minimize to the greatest extent possible the contingency of the block sticking to the 25 upper plate. While not deemed essential the ridges on the lower plate 14 may also be rounded.

The present inventor believes himself to be the first to produce a clamp for heel 30 presses which will prevent an appreciable adherence, of the heel block under pressure, to the press plates of the clamp. From the foregoing description it will be understood that the essential feature of the construction 35 is the reduction of the area of the material, of which the press plates are formed, which permits a union between plate and block when paste is interposed therebetween. By means of a sufficient reduction of such area 40 the liability of disaster due to adherence of the heel block to the clamp is so minimized as to be negligible. Preferably the normal area of the acting, or heel block contacting, face of each press plate is reduced to such 45 an extent as to prevent a sufficient amount of paste to gather between said face and the block to cause adhesion to an objectionable degree. As hereinbefore described this is accomplished by providing an interrupted 50 face on the press plates comprising alternate portions of the press plate material and air spaces, but under the broader aspect of the invention the desired result may be obtained by constructing a press plate having 55 the work engaging plane of its face interrupted in any feasible way to form areas

which permit and which do not permit an adherence of paste thereto.

The nature and scope of the present invention having been indicated and the preferred embodiment of the invention having been specifically described, what is claimed as new, is:

1. A heel pressing machine having, in combination, a frame supporting oppositely 60 facing press plates at least one of which is provided with an interrupted surface acting to prevent undue adhesion between the heel block and plate and to permit a substantial pressure to be applied to the heel 65 block without materially affecting the shape of its surface, and means for closing said plates within the frame under pressure.

2. A heel pressing machine, having, in combination, a heel clamp including a press 70 plate having a surface comprising alternate ridges and depressions of such proportions as to permit a substantial pressure to be applied to the heel block without materially 75 affecting the shape of the surface and to prevent undue adhesion between the block and plate, and means for closing said clamp on the heel block.

3. A heel pressing machine, having, in combination, pressure producing mechanism 80 comprising two plates having interrupted surfaces of such construction as to reduce the heel block engaging area which permits adherence of paste, one of said plates being 85 yieldingly urged toward the other; and means for separating the plates to provide 90 for insertion and removal of the heel block.

4. In a heel pressing machine, pressure producing mechanism comprising opposed 95 press plates having corrugated heel block 90 contacting faces acting to prevent undue adhesion between the block and plates while permitting a substantial pressure to be applied without injury to the block.

5. A heel pressing machine, having, in 100 combination, a heel press for pasted heel blocks comprising upper and lower clamping members having interrupted heel block 105 contacting faces whereby the paste carried by the tread face and heel seat of the heel block is prevented from spreading into a thin film while the heel block is under pressure between said members, and means acting on one of said clamping members to move it toward the other and apply pressure to the heel block.

FRED V. HART.
